UNITED STATES PATENT OFFICE.

ADON JULIUS HOFFMAN, OF SYRACUSE, NEW YORK.

DRIVING MECHANISM FOR REVERSELY-ROTATABLE ELEMENTS.

1,159,767.

Specification of Letters Patent.

Patented Nov. 9, 1915.

Application filed October 12, 1912. Serial No. 725,498.

To all whom it may concern:

Be it known that I, ADON J. HOFFMAN, of Syracuse, in the county of Onondaga, in the State of New York, have invented new and useful Improvements in Driving Mechanism for Reversely-Rotatable Elements, of which the following, taken in connection with the accompanying drawings, is a full, clear, and exact description.

10 This invention relates to certain improvements in glove washing machines in the class set forth in my pending application No. 702,304, filed June 7, 1912, but refers more particularly to the means for intermittently rotating one of the brushes in reverse direction while the other brush is held stationary.

20 The main object is to reduce the jar, noise and friction incidental to the reversal of the direction of rotation and to thereby increase the durability and efficiency of the machine.

Another object is to simplify and reduce the number of parts necessary to effect this reverse operation and, at the same time, to 25 bring such parts into a more compact space and closer to the top of the vat than has heretofore been practised.

A further object is to provide simple means for locking the lowermost brush 30 against rotation and also to permit it to be easily removed through the open upper side of the vat when the upper brush and its supporting frame are rocked upwardly and rearwardly in the manner hereinafter described.

Other objects and uses relating to specific parts of the machine will be brought out in the following description.

In the drawings—Figures 1 and 2 are respectively a top plan and a front elevation of a glove washing machine embodying the various features of my invention. Fig. 3 is an enlarged transverse vertical sectional view through the upper portion of the machine taken on line 3—3, Fig. 1. Fig. 4 is a side elevation of the upper portion of the same machine showing the revolving brush and its supporting frame together with the counter shaft and gears mounted thereon. Fig. 5 is an enlarged detail sectional view, partly in elevation, of a portion of the bottom of the vat and also a portion of the lower brush, showing the means for locking

said brush against rotation. Figs. 6, 7 and 8 are detail sectional views of the driving gears for the rotary brush and means for shifting the relative positions so as to intermittently reverse the direction of rotation 60 of said brush. Fig. 9 is an end view of the clutch shifting device shown in Fig. 3.

In carrying out the objects stated, an upright cylindrical vat—1—of sheet metal is mounted in and upon the upper portion of a supporting frame—2—the desired distance from the floor or other support and is provided with a conical bottom—3—having a central outlet pipe—4—leading from its apex and provided with a normally closed valve—5—for controlling the discharge of water or other cleansing fluid from the vat. The top of the vat is normally closed by a circular cast metal lid—6—raised upon its upper edge or rim and provided with a pendant annular flange—7—fitting more or less closely upon the periphery of the ring to prevent leakage of the cleansing fluid at this point.

A pair of coaxial circular brushes—8—and—9—of nearly the same diameter as the interior diameter of the vat are mounted within said vat and coaxial therewith, the lower brush—9—being provided on its underside with a pendant lug—10—which interlocks with a coöperative recessed lug—11—on the bottom of the vat at one side of its axis to hold the lower brush against rotation and at the same time to permit it to be removed when necessary through the upper open side of the vat when the lid and upper brush are displaced from their normal positions in the manner hereinafter described. The upper brush—8—is provided with a central hollow hub—12—having an angular opening—13—in its upper end for sliding interlocking engagement with the lower angular end—14—of an upright shaft—15—the latter being journaled in and extending some distance above a bearing—16—on the center of the lid—6—so as to rotate freely thereon. The hub—12—is provided with a central cylindrical bore or socket—17—in which is fitted with an easy sliding fit an enlarged circular hub—18—on the lower end of the angular shank—14—and cooperates with the upper end of the hub to limit the downward movement of the upper brush—8—and also to cause said brush to be elevated upwardly 110

with the lid when the latter is rocked from its normal position. The upper end of the annular portion —14— of the shaft —15— abuts against the underside of the lid —16— to prevent upward movement of said shaft relatively to the lid. A bracket —19— is secured to the top of the lid by any fastening means, as bolts —20—, and is provided with a journal bearing —21—, alined with the bearing —16—, for receiving the upper end of the shaft —15—.

A mangle wheel or disk —22— is rigidly secured to the extreme upper end of the upright shaft —15— and engages the upper end of the bearing —21— to hold the shaft against downward movement relatively to the lid —6—, said mangle wheel being provided with a circular series of radial bars or teeth —23— concentric with its axis of revolution and spaced apart to form intervening pins —24— alternating with the teeth —23— to permit intermeshing engagement of a pinion —25— with the same teeth from either side of the disk for the purpose of rotating the upper brush intermittently and alternately in reverse directions in the manner presently described. This pinion —25— is secured to the inner end of a radial projecting flexible shaft, composed of sections —26— and —27—, which are connected to each other by a universal joint —28—, the shaft section —26— being journaled in a suitable bearing —29— radially of and in substantially the same horizontal plane as the mangle gear —22— while the section —27— is movable vertically and is guided in an upright slotted arm —30— on the bracket —19—.

The upright slot, as —31—, of the arm —30— through which the shaft section —27— extends is in axial alinement with and some distance to the inner side of the shaft section —26— and is of substantially the same transverse width as the diameter 45 of the shaft section —27— and is of just sufficient length vertically to allow the pinion —25— to move from a position above to a position below the mangle gear —22— and vice versa to mesh with either side thereof. 50 That is, the portions of the arm —30— at opposite ends of the slot —31— form limiting stops to prevent undue displacement of the pinion from the gear and also to hold said pinion in mesh with either side thereof. 55 A portion of one side of the mangle gear —22— and adjacent portions of the teeth thereof are cut away to form a recess —32— opening from the periphery thereof and of sufficient circumferential length to permit 60 the pinion —25— to readily pass therethrough from one side to the other of the gear for intermittently rotating said gear and upper brush in reverse directions at each revolution of the gear, and, in order to 65 accomplish this shifting movement of the

pinion positively, I provide the recessed side of the gear with oppositely disposed concave deflectors —33— and —33'— adapted to be engaged by a conical stud —34— centrally on the inner end of the pinion —25—. 70 These deflectors —33— and —33'— are secured together (preferably integral) base to base substantially midway between and concentric with the corresponding adjacent teeth at opposite sides of the recess —32— 75 and are substantially semi-circular, each having a radius substantially equal to the radial distance between the root of any one of the teeth of the pinion —25— and opposite face of the conical stud —34— so as to hold the pinion in mesh with the end teeth of the gear while traveling from the upper side to the lower side thereof through the opening or recess —32— as shown more clearly in Figs. 6, 7 and 8. 85

Driving means for the flexible shaft.—Secured to the outer end of the section 26 of the flexible shaft is a gear —35— meshing with a pinion —36— which is loose on a stationary stud —37—, the latter being rigidly secured to a bracket —38— on the adjacent side of the upper portion of the vat —1— and extends radially therefrom. A pulley —39— is loosely mounted upon the stud —37— at the outer end of the pinion —36— and adapted to be connected by a belt to any available source of power (not shown), the adjacent ends of the hubs of the pulley —39— and pinion —36— being provided with clutch members —40— for interlocking engagement to transmit motion from the pulley to the pinion, but are normally disengaged by coil spring —41— surrounding the stud —37— between the adjacent ends of the pulley and pinion as shown more clearly in Figs. 1, 2 and 3. 105

A shifting member —42— is loosely mounted on the stud —37— at the outer end of the pulley —39— and is held against axial displacement from the stud by a collar —43— which is rigidly secured to the stud. The outer face of the hub of the shifting member —42— is provided with an automatically convexed rib —44— movable into and out of registration with a convex seat —45— in the adjacent face of the collar —43— so that, when the shifting member —42— is rotated, the convex rib —44— rides upon the face of the collar —43— to one side of the recess for forcing the pulley —39— endwise inwardly against the action of the spring —41— to engage the clutch members —40— with each other and thereby lock the pulley to the pinion —36— for rotating the upper circular brush —8— through the medium of the gear —22—, pinion —25— and flexible shaft sections —26— and —27—. The periphery of the collar —43— is provided with limiting stops —46— adapted to be engaged by a 110

coöperating shoulder —47— on the periphery of the shifting member —42— to limit the degree of rotation of said shifting member and to hold it against rotation with the pulley, said shifting member being rotatable in either direction from its normal positions and constitutes a stop for limiting the outward axial movement of the pulley.

Another bracket —38—, similar to that previously described, is secured to the diametrically opposite side of the vat, said brackets being provided with parallel rearwardly extending arms having lengthwise upwardly arched slots —48— extending from the center to points some distance beyond the rear of the vat for the reception of radially projecting guide pins —49— on diametrically opposite sides of the lid —6— as shown more clearly in Fig. 3. These slots —48— are disposed in a plane above the rim or top of the vat a sufficient distance to permit the lid together with the upright shaft —15— and upper brush —8— to be rocked upwardly and rearwardly to the position shown in Fig. —4— or until the brush and lid assume a substantially vertical position edgewise.

The front ends of the slots —48— are disposed vertically in a plane substantially coincident with the longitudinal center of the vat so as to hold the lid against forward and rearward movement when in its closed position. It will also be observed that the flexible shaft sections —26— and —27—, carrying respectively the gear —35— and pinion —25— are mounted upon the lid and are movable therewith, thus disengaging the gear —35— from its driving pinion —36— as shown in Fig. —4—.

40 Operation.—Assuming that the lower brush —9— is placed in operative position and interlocked with the stud —11— and that the gloves to be cleansed have been placed in a vat, containing a cleansing fluid, the lid —6— being closed to bring the upper brush into coöperative coaction with the lower brush, said upper brush being movable vertically a limited distance along the angular shank —14— to accommodate this to the varying quantities of gloves which rest upon the lower brush. Now, by shifting the member —42— in one direction or the other from its normal position, the pulley —39— which rotates continuously will be forced into clutching engagement with the pinion —36—, thereby permitting rotary motion to the gear —35—, flexible shaft sections —26— and —27— and pinion —25—. This pinion —25— is, therefore, rotated continuously in the same direction when the clutch members —42— are in engagement and will impart rotary motion to the upper brush —8— through the medium of the mangle gear —22— and shaft —15—, the direction of rotation of the brush depending upon

the position of the pinion —25— above or below the mangle gear. During this rotation of the upper brush, as soon as the recess —32— in the side of the mangle gear is brought into registration with the pinion or conical stud —34— on the inner end of said pinion will engage the approaching deflector —33— or —33'— according to the direction of rotation of said mangle gear, and such deflector, coacting with the stud, will diametrically rock the pinion —25— through the recess to engage the opposite side of the mangle gear thereby reversing the direction of rotation of the brush, this operation being repeated at each revolution of the brush or as often as the recess —32— is registered with the pinion —25—. After the gloves have been thoroughly cleansed, the shifting member —42— may be again operated to release the pulley —39— from interlocking connection with the pinion —36—, such release being effected by the spring —41— after which the lid —6— and upper brush, carried thereby, may be rocked upwardly and rearwardly by means of suitable handles, shown in Fig. 1, until the lid is thrown to the rear of the vat and together with the brush stands in a nearly vertical position thus leaving the vat open for the removal of the cleansed gloves. If the first cleansing is not sufficient, the cleansing fluid may be drawn off by opening the valve —5— and a fresh supply of clean or different fluid may be placed in the vat, the lid closed and the operation previously described repeated.

What I claim is:

1. In a glove washing machine, in combination with a rotary vertical shaft, a stationary horizontal shaft, a continuously rotating driving pulley and a pinion, both rotatable loosely on the stationary shaft and provided with coöperative clutch faces normally spring-pressed apart, means including a hand-piece operable at will to shift the pulley axially against the action of the spring to engage the clutch faces for driving the pinion, and mechanism driven by the pinion for driving the vertical shaft first in one direction and then in an opposite direction.

2. In a glove washing machine, in combination with a vertical rotary shaft, a stationary horizontal shaft, a continuously rotating driving pulley and a pinion, both rotatable loosely on the stationary shaft and provided with coöperative clutch faces normally spring-pressed apart, means on the stationary shaft including a hand-piece operable at will for shifting the pulley axially against the action of the spring to engage the clutch faces for driving the pinion, a gear meshing with and rotated continuously by the pinion when the clutch faces are engaged, and coöperative connections between

the gear and vertical shaft for driving said vertical shaft first in one direction and then in an opposite direction.

3. In a glove washing machine, in combination with a vertical rotary shaft, a stationary horizontal shaft, a continuously rotating driving pulley and a pinion, both rotatable loosely on the stationary shaft and provided with coöperative clutch faces normally spring-pressed apart, means on the stationary shaft including a hand-piece operable at will for shifting the pulley axially against the action of the spring to engage the clutch faces for driving the pinion, a gear meshing with and rotated continuously

by the pinion when the clutch faces are engaged, and coöperative connections between the gear and vertical shaft for driving said vertical shaft first in one direction and then in an opposite direction, said gear and parts 20 driven thereby being movable relatively to the stationary shaft to disconnect the gear from the pinion.

In witness whereof I have hereunto set my hand this 5th day of September, 1912. 25

ADON JULIUS HOFFMAN.
